UNITED STATES PATENT OFFICE.

EDGAR W. SUMMERS, OF PITTSBURGH, PENNSYLVANIA.

RAILWAY-CAR TRUCK.

1,158,331.

Specification of Letters Patent.

Patented Oct. 26, 1915.

Application filed March 2, 1915. Serial No. 11,535.

To all whom it may concern:

Be it known that I, EDGAR W. SUMMERS, a resident of Pittsburgh, in the county of Allegheny and State of Pennsylvania, have 5 invented a new and useful Improvement in Railway-Car Trucks, of which the following is a specification.

This invention relates to railway car trucks.

10 The objects of the invention are to provide an improved truck embodying a side frame formed largely of rolled sections which can be made up and shipped as a unit and does not have to be assembled on 15 the ground; wherein the lower or tension member is entirely in tension and the upper member in compression, said members not being subjected to vertical bending strains; which is much lighter but nevertheless is 20 stronger than rolled or forged steel side frames as usually constructed; which is adjustable with reference to the journal boxes to compensate for a turned down wheel to thereby maintain the couplers at the stand- 25 ard elevation; whose net cross section is a maximum for the weight of metal used; whose compression and tension members are secured to each other and to the other parts by a single row of rivets along the 30 center lines of said members; and which truck also embodies a special arrangement of the springs for supporting the truck bolster to economize space, for reasons which will more fully hereinafter appear.

35 Other objects of the invention are in part obvious and in part will appear more fully in detail hereinafter.

The invention comprises the railway car truck hereinafter described and claimed.

40 In the drawings, Figure 1 is a side elevation, partly in section on the line 1—1, Fig. 2, showing one form of car truck adapted for an ordinary truck bolster; Fig. 2 is a sectional elevation on the line 2—2, 45 Fig. 1, looking in the direction of the arrows; Fig. 3 is a side elevation, partly in section, of another form of car truck embodying the invention, and showing a

special arrangement of the bolster supporting springs; Fig. 4 is a sectional elevation on the line 4—4, Fig. 3, looking in the direction of the arrows; Fig. 5 is a detail plan view, showing the arrangement of the bolster springs; Fig. 6 is a detail sectional elevation, on a larger scale, taken on the line 6—6, Figs. 1 and 3; Fig. 7 is a similar view, showing the arrangement when using a turned down wheel; Fig. 8 is a detail section on the line 8—8, Figs. 1 and 3; Fig. 9 is a detail sectional view through one of the 50 55 60 65 70 75 80 85 90 95 rolled members of the side frame; and Fig. 10 is a detail cross sectional view, showing another way of securing the webs of the compression and tension members to each other.

The truck side frame shown in the drawings comprises an upper or compression member 1, a lower or tension member 2, column posts 3 and pedestals 4. The compression and tension members 1 and 2 are 70 preferably formed on an I-beam section, the webs of said members being horizontal and their flanges vertical. In this position the metal is most efficiently distributed to resist lateral bending strains.

The compression member 1 is preferably arched upwardly slightly while the tension member 2 is preferably bent downwardly as shown. The column posts 3 are preferably steel castings of suitable form and provided at the top and bottom with flanges, marked 5 and 6 respectively, fitting between the flanges of the members 1 and 2 and seated against and secured to the webs thereof by rivets 7.

The upper and lower members 1 and 2 at both ends are so formed or arranged as to lie parallel to each other with their webs in contact, enabling them to be secured together rigidly and solidly by one or more rivets 9 passing through said webs. Preferably, the webs are brought together by shearing off the adjacent end portions of the flanges, as shown at 8. Fig. 6, although the same result can be secured in various other ways, as by bending the webs of the two

members toward each other, as at 8^a, Fig. 10, in which case the frame is narrower at its ends than in the middle.

The frame is braced and reinforced at 5 the angles between the upper and lower members by triangular plates or gussets 10 having flanges 11 fitting against the webs of members 1 and 2 and secured thereto by rivets 12. These gussets prevent localization 10 of bending stresses in the end portions of the frame, such as are caused by braking force, or momentum of the car or truck in stopping, starting or striking bumps or 15 obstructions, and distributes and applies said stresses to the upper and lower members of the frame at some distance from their connection to the journal box and axle. This is of particular advantage in case the cross section of the end portions of the frame 20 members is reduced by shearing off the flanges, as shown in Fig. 6, since the bending forces are then applied to the upper and lower members where they are of full cross section and have maximum resistance to 25 bending strains.

The holes in the members 1 and 2 for the rivets 7, 9 and 12 are all of substantially the same size and are located in the central longitudinal plane of the side frame, 30 so that the net or effective cross section of the members 1 and 2 is a maximum for the amount of metal used. The usual column bolts are omitted and therefore it is unnecessary to punch large holes in the compression 35 and tension members for said bolts, thereby reducing the total weight of the side frame.

The upper and lower members 1 and 2 are so supported that lines through their centers of gravity intersect directly above the 40 centers of the journal boxes 13. Consequently, the vertical load does not subject said members to bending stresses near their ends. The journal boxes are provided on their upper surfaces with longitudinal, parallel flanges 14 forming therebetween a seat to receive the pedestals 4, said flanges preventing escape of the side frame from the journal boxes and also any lateral movement therebetween. The pedestals are hollow 45 steel castings having depending jaws 15, 16 lying at the sides of the journal box and preventing relative movement between the side frames and journal boxes longitudinally of the car. They have flat bases 17 resting 50 on the upper surface of the journal box between the flanges 14, and their upper portions are shaped to fit between the flanges of the tension member 2 and have a firm seat against the web thereof. Said pedestals 55 have a horizontal portion lying underneath the parallel horizontal portions of the members 1 and 2 and an inclined portion lying underneath the downwardly inclined portion 60 of the tension member 2, as shown in Fig. 1,

and are secured to said member by the same 65 rivets 9 and 12 which secure the tension member to the upper member 1 and to the gusset plates 10. The journal box is also provided on its upper surface between the flanges 14 with an upright boss 18 passing 70 through an opening in the pedestal 4 and having a threaded opening to receive a bolt 19 passing through openings in the webs of members 1 and 2 at their junction and also through an opening in the roof of the pedestal 4. Said bolt is screwed up tight and is fastened by a suitable lock washer 20 so as to secure the side frame to the journal box and enable the wheels and axle to be lifted with the truck. By inserting one or more 80 shims or filler plates 21 between the pedestals 4 and the upper surface of the journal box, as shown in Fig. 7, the side frame may be adjusted to compensate for a turned down wheel to thereby maintain the car couplers 85 at the standard level, as will be readily understood.

The parallel flanges 14 on the journal box 90 are preferably farther apart than the overall distance between the flanges of the tension member 2, which at the point marked 95 22 in Fig. 1 comes fairly close to the journal box itself and lies between the flanges 14 thereon. This enables a heavier I-beam section to be used for the tension and compression members for a truck on an extra heavy car. The section of the extra heavy side frames will be increased by increasing the thickness of the flanges of the I-beams, as indicated by the dotted lines 23 in Fig. 9, 100 which locates the additional metal in the best position to resist lateral bending strains. With the flanges 14 on the journal box 105 widely separated, as described, the same journal box can be used with different weights of side frame.

In the forms shown in Figs. 1 and 2, the bolster springs are supported on suitable seats in the ends of the spring plank 24, which is a light channel member extending 110 across from side frame to side frame and riveted or otherwise secured at its ends to the saddles 25. The saddle is a steel casting provided at its opposite ends with feet 26 fitting between and resting on the upper 115 flanges of the tension member 2 and seated on the web thereof, as shown in Fig. 2. Intermediate said feet the saddle is provided with a depending cross web or flange 27, also seated on the web of the tension member and 120 having a depending projection 28 fitting a hole in the web of the tension member, said projection acting as a key to lock the saddle to the tension member and prevent it from sliding therein. The tension member 2 is 125 wholly free of sharp angles or bends beneath or adjacent to the spring seat, its two upwardly inclined portions being connected

by a uniformly curved portion, shown in Fig. 1, on which the saddle 25 is supported. The spring saddle distributes its load uniformly along the curved portion of member 2 so that said member is wholly in tension and is not subjected to any bending strains whatever.

The truck shown in Fig. 1 is arranged to accommodate the usual truck bolster (not shown), which slides between the guides on the column posts 3 and is supported on the usual four springs arranged in pairs of two each side by side. In assembling, the side frames are first fastened to the journal boxes, 15 the bolster is inserted endwise and lifted to position, the spring plank is inserted endwise and the saddles thereon are dropped into their seats in the curved portions of the tension members, and the bolster springs are 20 then placed between the bolster and their seats on the spring plank.

Fig. 3 shows a modified form of the invention embodying a special arrangement of the bolster supporting springs. This is like 25 that of Fig. 1, except in the following particulars: The column posts 3^a are of special design, and are located a little farther apart than as shown in Fig. 1. The spring plank 24^a is also a light channel member riveted at 30 its ends to a channel-shaped inwardly extending projection 30 on the saddle 31 which rests on the upper edges of the flanges of the tension member 2, as indicated at 32, and is provided with depending parallel flanges 35 33 seated on the web of said member. These flanges extend up over the lower flanges 6, 6^a of the column posts 3, 3^a and are seated thereon, and the upper surface of the saddle is also stepped, as shown in Fig. 3, to provide 40 two sets of seats, marked 34 and 35, at different elevations for the four bolster supporting springs 36. These springs are all located in the same plane, so that the side frame as a whole is narrower than as shown 45 in Fig. 1. This arrangement provides additional space above the springs on the side toward the king pin for equalizing car supporting levers (not shown) of the type shown in my co-pending application for rail- 50 way car truck, filed December 29, 1914, Serial No. 879,499, so that said levers may have a greater range of movement without interference by the springs or adjacent portions of the side frame.

55 The railway car truck described is simple and can be manufactured and assembled at low cost. It is made largely of rolled sections so that it is very strong for the weight of metal employed and its total weight can be reduced without decreasing the strength of the truck. It can also be assembled and shipped as a unit and does not have to be built up at the time of assembling it in the car. It also enables the axle and wheels to

be lifted with the truck and provides a compensating adjustment for turned down wheels. The special arrangement of springs also enables equalizing car supporting levers to be employed, such as shown in my co-pending application referred to, with a greater range of movement thereof and without interference between said levers and the springs or other parts of the car truck.

It will, of course, be understood that the invention is not limited to the exact details of construction shown in the drawings, but is capable of considerable modification within the scope of the claims appended hereto.

What I claim is:

1. A car truck side frame of the arch bar type, comprising a compression member and a tension member, each formed of an I-beam section placed with the web horizontal and the flanges vertical. 80
2. A car truck side frame of the arch bar type, comprising a compression member and a tension member, each formed of an I-beam section placed with the web horizontal and the flanges vertical, said members being riveted together at their ends, and column posts connecting said members and riveted thereto. 85
3. A truck side frame of the arch bar type, comprising a compression member and a tension member, each formed of an I-beam section placed with the web horizontal and the flanges vertical, said members having their end portions parallel and secured together. 95
4. A truck side frame of the arch bar type, comprising a compression member and a tension member, each formed of an I-beam section placed with the web horizontal and the flanges vertical, said members having their end portions parallel and formed to bring the webs into contact and being riveted together through said webs. 100
5. A truck side frame of the arch bar type, comprising a compression member and a tension member, each formed of an I-beam section placed with the web horizontal and the flanges vertical, said members having their end portions parallel and having their adjacent flanges at said end portions cut off to bring the webs into contact and being riveted together through said webs. 110
6. A truck side frame of the arch bar type, comprising a compression member and a tension member, said members having their end portions secured together and adapted to rest upon the journal boxes, said members having their centers of gravity intersecting vertically over the centers of rotation of the axles. 120
7. A truck side frame of the arch bar type, comprising a compression member and a tension member each formed of a rolled section placed with the web horizontal and the flanges vertical, said members having

- their end portions secured together and adapted to rest upon the journal boxes, said members having their centers of gravity intersecting vertically over the centers of rotation of the axles. 5
8. A truck side frame of the arch bar type, comprising a compression member and a tension member each formed of an I-beam section placed with the web horizontal and the flanges vertical and having their end portions secured together through said webs and arranged to rest on the journal boxes, said members having their centers of gravity intersecting vertically over the centers of rotation of the axles. 10
9. A truck side frame of the arch bar type, comprising a compression member and a tension member each formed of an I-beam section placed with the web horizontal and the flanges vertical, said members having their end portions parallel and formed to bring the webs into contact and being secured together through said webs, and gussets located in the angles between the end portions of said members and being riveted thereto. 15
10. A truck side frame of the arch bar type, comprising a compression member and a tension member each formed of a rolled section with a horizontal web and vertical flanges and having their end portions secured together, said members having their centers of gravity intersecting vertically over the centers of rotation of the axles, and gussets located in the angles between the end portions of said members and being riveted thereto. 20
11. A truck side frame of the arch bar type, comprising a compression member and a tension member having their end portions secured together, pedestal jaw members secured to said end portions and also to the adjacent portions of the tension member, and gussets located in the angles between the end portions of said members and riveted thereto. 25
12. A truck side frame of the arch bar type, comprising a compression member and a tension member each formed of a rolled section with a horizontal web and vertical flanges, said members having their end portions with the webs in contact and secured together through said webs, pedestal jaw members secured to said end portions and also to the adjacent portions of the tension member, and gussets located in the angles between the end portions of said members and riveted thereto. 30
13. A truck side frame of the arch bar type, comprising a compression member and a tension member having their end portions secured together, pedestal jaw members secured to said end portions and also to the adjacent portions of the tension member, said members having their centers of gravity intersecting vertically over the centers of rotation of the axles, and gussets located in the angles between the end portions of said members and riveted thereto. 35
14. A truck side frame of the arch bar type, comprising a compression member and a tension member each formed of a rolled section with a horizontal web and vertical flanges and having their end portions parallel with the webs in contact and secured together through said webs, pedestal jaw members secured to said parallel end portions and also to the adjacent portions of the tension member, said members having their center of gravity intersecting vertically over the centers of rotation of the axles, and gussets located in the angles between the end portions of said members and riveted thereto. 40
15. A truck side frame of the arch bar type, embodying a tension member formed of an I-beam section placed with its web horizontal and its flanges vertical and having a curved lower portion with the inclined portions in tangent thereto, and a spring supporting member resting on the curved portion of said tension member and arranged to distribute the load thereon, whereby bending stresses in said tension member are avoided. 45
16. In a car truck, a side frame embodying a compression member and a tension member having their ends parallel and united together, pedestal members secured to said parallel end portions, a journal box in each of said pedestal members, and a bolt passing vertically through the pedestal members and the parallel end portions of the side frame members and securing said journal boxes to the side frame. 50
17. In a car truck, a side frame embodying a compression member and a tension member having their ends parallel and united together, pedestal members secured to said parallel end portions, a journal box in each of said pedestal members, a bolt passing vertically through the pedestal members and the parallel end portions of the side frame members and securing said journal boxes to the side frame, and means adapted to permit relative vertical adjustment between said journal boxes and side frame. 55
18. In a car truck, a side frame embodying a compression member and a tension member having their ends parallel and united together, pedestal members secured to said parallel end portions, a journal box in each of said pedestal members, a bolt passing vertically through the pedestal members and the parallel end portions of the side frame members and securing said journal boxes to the side frame, and adjusting shims located between the journal boxes and pedestal members. 60
19. A truck side frame of the arch bar type, comprising a compression member and a tension member having their end portions secured together, pedestal jaw members secured to said end portions and also to the adjacent portions of the tension member, said members having their centers of gravity intersecting vertically over the centers of rotation of the axles, and gussets located in the angles between the end portions of said members and riveted thereto. 65

type, comprising a compression member and a tension member each formed of a rolled section with a horizontal web and vertical flanges, said members having their end portions parallel with the webs thereof in contact, pedestal members secured to said parallel end portions, column posts, gusset plates located in the angles between the end portions of said compression and tension members, and a single row of rivets in the cen-

tral longitudinal line of said side frame for securing said tension and compression members to each other, to said pedestals, column posts and gusset plates.

In testimony whereof, I have hereunto set my hand.

EDGAR W. SUMMERS.
